UNITED STATES PATENT OFFICE.

CHARLES E. BEAN, OF FALL RIVER, MASSACHUSETTS.

DESIGN FOR KNIT FABRICS.

Specification forming part of Design No. **11,552**, dated December 30, 1879; application filed September 3, 1879.
[Term of patent 3½ years.]

To all whom it may concern:

Be it known that I, CHARLES E. BEAN, of Fall River, in the county of Bristol and State of Massachusetts, have invented a new and Improved Design for Knit Fabrics, of which the following is a specification.

The design is intended for fabrics to be used in the manufacture of knit garments, such as undershirts, drawers, &c., and is represented by the accompanying drawing.

A represents a portion of a garment, such as an undershirt. The fabric is knit of white and colored yarns, or of two yarns of different colors, so that the body of the fabric has zigzag lines of the two colors alternately, and it is ornamented by parallel stripes *a*, which show only one color. The stripes *a*, of solid color, are about one-third the width of the intervening spaces, and when combined in the manner described with the braided or zigzag

lines of the intervening spaces give to the garment an ornamental and attractive appearance. Any desired color may be used, such as red, blue, brown, and others.

I am aware that stocking-legs have been made with longitudinal stripes of alternate colors; but

What I claim, and desire to secure by Letters Patent, is—

A design for knit fabrics for underwear, consisting of a ground or body having waving or zigzag lines of alternate colors running crosswise of the fabric, ornamented by narrow parallel stripes *a*, of solid color, running longitudinally of the fabric, substantially as shown and described.

CHARLES EDWIN BEAN.
